CLAIM

The ornamental design for a combined container cap and medication reminder, as shown.

DESCRIPTION

FIG. 1 is a perspective view of a combined container cap and medication reminder embodying my new design;

FIG. 2 is a top plan view;

FIG. 3 is a front elevational view;

FIG. 4 is a side elevational view; and,

FIG. 5 is a bottom plan view.

The dash lines showing a numeral and a container are for the purposes of showing environmental use only.

FIG. 2

FIG. 3

FIG. 5

FIG. 4
